UNITED STATES PATENT OFFICE.

PETER KUZMJAK, OF CONNELLSVILLE, PENNSYLVANIA.

DESIGN FOR A PAIR OF TONGS.

55,385.

Specification for Design.

Patented June 1, 1920.

Application filed February 9, 1920. Serial No. 357,366. Term of patent 14 years.

To all whom it may concern:

Be it known that I, PETER KUZMJAK, a citizen of Czecho-Slovakia, residing at Connellsville, in the county of Fayette and State of Pennsylvania, have invented a new, original, and ornamental Design for Tongs, of which the following is a specification, reference being had to the accompanying drawing, forming part thereof.

The figure is a view in perspective of a pair of tongs, showing my new design.

I claim:—

The ornamental design for a pair of tongs, as shown.

PETER KUZMJAK.
